UNITED STATES PATENT OFFICE.

JOHANNES HUNDHAUSEN, OF HAMM, GERMANY.

DRIER FOR SEMIFLUID MATERIAL.

SPECIFICATION forming part of Letters Patent No. 594,085, dated November 23, 1897.

Application filed June 10, 1896. Serial No. 594,971. (No model.)

To all whom it may concern:

Be it known that I, JOHANNES HUNDHAUSEN, a subject of the King of Prussia, and a resident of Hamm, in Rhenish Prussia and Kingdom of Prussia, Germany, have invented certain new and useful Improvements in the Method of and Apparatus for Drying Semifluid and Like Materials, of which the following is a specification.

This invention relates to the method of and apparatus for drying semifluids and like substances, such as syrups and various slimy and sticky products.

According to this invention the substance to be dried is fed in thin layers upon rotating surfaces or cylinders which may be heated internally or externally, or both, with or without the assistance of an air-current.

It will be obvious that many arrangements of the drying-cylinders may be employed in such a manner that the material to be dried thereon may be applied to their rotating surfaces, from which it finally drops or is scraped off. By depositing the substance in uniform thin layers upon the rotating cylinders it is prevented from flowing off and is in the best condition for giving up its moisture. As the layers of material being dried are to be very thin, it follows that the cylinders must not be heavy nor require considerable driving power and that their surfaces must be perfectly smooth, as irregularities produce corresponding irregularities in the thickness of the layer. Hence when the ordinary thickness of the layer is dried and drops off a thicker part will not be dry and will continue to adhere to the cylinder, exaggerating the defect in successive layers of the material coming on the cylinder to be dried.

The following three conditions are to be observed: First, the surface of each cylinder must be as large as possible; second, each cylinder must be rotatable with a small expenditure of energy; third, the surface of the cylinder must be as smooth as possible.

These conditions must be borne in mind in the construction, first, of the cylinder, and, second, of the whole system:

First. The cylinder must not be constructed of cast metal nor of riveted or soldered sheets, because the cylinder would in the first case be too heavy and in the second case its sur-

face would not be sufficiently smooth. Each cylinder should have a diameter of at least twelve inches, and it cannot, therefore, be drawn or pressed in one piece. I find that the cylinder is therefore best constructed of thin sheet metal with the edges of the metal electrically welded. The seam produced is reduced by grinding it down. A cylinder so constructed having a length of six feet six inches and a circumference of three feet three inches has a weight of only twenty-two pounds.

Second. The system which I prefer to employ is illustrated by the accompanying drawings and hereinafter described with reference thereto.

In the drawings, Figure 1 represents a vertical section, and Fig. 2 a sectional plane.

The ends of the cylinders C are fitted with centers, on which are formed or secured coaxial pinions S S, bored for the reception of spindles upon which the cylinders can rotate. The series of cylinders C are mounted parallel with each other upon and between two parallel frames B B, upon which the pinions S S can run and by means of which the cylinders will be caused to rotate. This arrangement is found to be preferable to that of a rack on the frames gearing with the wheels S S, inasmuch as the linear expansion of the rack under heat increases the pitch of the rack-teeth and prevents perfect gearing and smooth action. Parallel with and outside the frames B B there are endless chains k, running upon the chain-wheels K K', of which the wheels K have their axes in fixed bearings and the other, K', in adjustable bearings, so that the chains may be kept tight with variations of temperature by moving the bearings of K' farther from or nearer to K by means of the hand-wheels T, as may be required. The chains carry at suitable intervals spindles R, which are fitted into the holes in the wheels S, and thus form centers upon which the cylinders can rotate. The wheel K being rotated by suitable power and gearing the whole system of cylinders is caused to travel around their axes by the contact of their wheels with the frames. The frames are made adjustable, together with the wheel K', and for the same reason, by means of an overlapping joint.

The apparatus is arranged within a chamber A through an opening E, in which the material can be supplied to the roller. Between the ends of the series of cylinders there 5 may be arranged suitable heating appliances, and at F there may be an inlet for the hot air. The number of cylinders will in every case be determined by the nature and amount of work to be done and in the simplest cases one 10 such cylinder may be sufficient. When the material is dry, it falls from the cylinders into the bottom of the chamber, whence it may be removed.

Having now described my invention, what 15 I claim is—

A drying apparatus comprising a series of cylinders, an endless chain for moving said cylinders, driving means for the said chains, parallel frames B and pinions S carried by the spindles of the cylinders and engaging the frames B to rotate the cylinders, substantially as described.

Signed at Cologne, in the Province of Rhine-land and Kingdom of Prussia, Germany, this 31st day of March, A. D. 1896.

JOHANNES HUNDHAUSEN.
